BIFURCATED UNDERGARMENT

Isadore Lawrence Lesavoy, Allentown, Pa.

Application February 4, 1936, Serial No. 62,237

1 Claim. (Cl. 2—224)

The invention relates in general to bifurcated under-garments of the type commonly identified as panties, bloomers, trunks, pajamas and like feminine articles of apparel.

5 The primary object of the invention is to provide an improved, simplified, easily constructed under-garment of the type outlined which will provide a fashioned fit form to snugly fit the crotch of the wearer without binding and on the contrary to provide for a freedom of movement 10 on the part of the wearer without rubbing or chafing by the garment and at the same time provide for the smoothness of outer contour and elimination of bulky or raised parts required by 15 present fashion in women's clothing.

Apparel of this character as heretofore constructed developed a line of weakness along the 20 seams at the crotch portion of the garment, with the result that any abnormal strain would cause 25 the garment to tear along the line of courses of the fabric forming the crotch portion and this weakness became more prevalent with the prolonged use or age of the article.

Accordingly another object of the invention is 25 to provide a form of construction of the crotch portion which would tend to strengthen and reinforce these regions of weakness so as to prolong the life of the garment and at the same time avoid any necessity for providing extra or reinforcing material which would add bulkiness to 30 the parts reinforced.

Broadly, this aspect of the invention is obtained by disposing the crotch seams at an angle to the texture of the fabrics which form the 35 seams. Differently expressed the disclosure herein features the cutting of the edges of the several sections of material which form the crotch portion of the garment along biased lines so that strain on the finished seams will extend across 40 both the woof and warp lines of the fabric.

Various other objects and advantages of the 45 invention will be in part obvious from an inspection of the accompanying drawing and in part will be more fully set forth in the following particular description of one form of mechanism embodying the invention, and the invention also consists in certain new and novel features of construction and combination of parts hereinafter set forth and claimed.

50 In the accompanying drawing:

Figure 1 shows in full lines a tubular blank folded flat and constituting a body portion and in dotted lines the opposite ends of the crotch forming section of the finished garment illustrating a preferred embodiment of the invention;

55 Figure 2 is a plan view of one of the two identical sections which form the crotch;

Figure 3 is a perspective view of the crotch forming portion made from two of the sections 60 shown in Figure 2;

Figure 4 is a detailed view in elevation of the lower right hand portion of the tubular blank shown in Figure 1, looking at the same from the lower right hand side of the figure;

Figure 5 is a sectional view taken on the vertical medial plane of the completed garment; and

Figure 6 is a view in front elevation of the garment shown in Figure 5 with the crotch portion elevated to show opposite ends thereof.

The garment is formed primarily of two major 10 parts, a knitted tubular member 10 shown in plan in Figure 1, and a crotch forming portion 11. The crotch forming portion is formed of two similar sections 12, one of which is shown in Figure 2.

15 The tubular member 10 when laid flat as shown in Figure 1 has a straight lower edge 13 and a slightly inclined upper edge 14 cut on the bias from the original cut of the material indicated by the dotted line. This has the effect of making 20 the front shorter than the rear so as to bring the completed garment slightly higher at its rear portion than at its front portion. The lower edge 13 is slit at diametrically opposite portions along intersecting curved lines 15 and 16 to form a 25 front notch 17 and a rear notch 18, both of curve-sided V-shape or parabolic form shown in Figure 4. It is a feature of this disclosure that the lines 15 and 16 are cut at an angle to the line defining the woof 19 and to the line forming the warp 30 20 of the fabric. While these may be along straight lines preferably they are of slightly concaved form shown in the several figures.

The main body forming member 10 is preferably formed without the side seams usually found 35 in garments of this character and for this reason is shown herein to be a seamless tube of knitted material. In the finished garment this member 10 forms the front 21, the rear 22, sides 23 and 24 and all of the legs 25 and 26 except that inner 40 portion of each leg which is continuous with the crotch portion. It is noted that the notch or recess 18 at the rear of the garment is of greater depth than the recess 17 at the front of the garment so that in the finished structure there is 45 more material provided to form the deeply bellied rear 22 than is need to form the more or less flat front 21.

Referring to either one of the two sections 50 which go to make up the crotch portion shown in Figure 3, it will be noted by specific reference to the showing in Figure 2 that the section 12 is of quadrilateral form having a long straight edge 27, extending parallel to the courses 28 of the fabric, the end edges 29 and 30 are slightly convex, being small segments of large circles and in each case extend from the opposite ends of the straight edge 27 forming included angles therewith which are relatively large; in the case of the edge 30 being about or slightly more than 90°, 55 60

and in the case of the edge 29 being slightly less than 90°. The edge 30 is materially longer than the edge 29 and these edges are so cut that they fit respectively in both dimension and curvature of angle with the edges of the slits 17 and 18. The fourth or top edge 31 shown in Figure 2 opposite the long edge 27 is of parabolic form and extends from the longer edge 30, forming a relatively small included angle at 32 and sharply rounding therefrom in a concave curve with its relatively flat end portion 33 meeting the shorter end edge 29 approximately at right angles thereto.

In forming the crotch portion 11, two of these sections are sewed together along their two concaved edges 31 to form a seam 34. As thus formed the crotch portion 11 will have a configuration with pointed ends, the included angles of which are in each case materially greater than 90° and are bisected by the line forming the seam 34 as particularly shown in Figure 6.

The pointed or arrow end 35 at the rear of the garment is wider than the arrow end 36 at the front of the garment. The pointed end 36 is fitted into the V-shaped notch 17 and is secured to the tubular member 10 by means of a seam 37. Similarly the wide arrow end 35 of the crotch section is fitted into the rear notch 18 and is secured to the body portion by means of a seam 38. It is a feature of this disclosure that the seams 37 and 38 extend at an angle to the courses of the material in both the body portion 10 and to the courses in both of the sections 12 which go to make up the crotch portion 11. The upper edge 14 is conventionally gathered and provided with an elastic to form a reduced waist 39.

While the invention is complete as thus far described, the present disclosure features additionally a structure to give shape to the leg. This is obtained by the peculiar shaping of the crotch forming section particularly shown in Figure 5. It is noted that the edges 29 and 30 converge downwardly so that the lower ends of these edges are closer together measured along the line 27 than the upper edge. Differently expressed the horizontal length of the section 12 gradually decreases towards the lower edge 27 and this has the effect of drawing the edge 15 from the position it originally occupied, as indicated by the dot and dash lines in Figure 5, to the position occupied by the seam 36, this having the effect of gradually decreasing the diameter of the leg to the minimum diameter at its lower edge and incidentally giving shape and form to the entire lower portion of the leg. A hem or binding 40 defines the lower edge of each of the legs and in each case extending along the edges 13 and 27.

It is appreciated that in those cases where extra reinforcement is required in the crotch portion, the section 12 may be made of two thicknesses of material. While it would not form a structure with all of the advantages herein claimed, it is obviously within the scope of the invention to make the crotch section of one piece of material and cut to the form shown in Figure 3 in those cases where it was desired for any reason to eliminate the seam 34. While the present disclosure features the use of a one-piece tubular member 10 it is obviously within the scope of the disclosure to form the body portion 10 of two or more parts seamed together to form the tubular structure.

The present disclosure permits the designing of

the crotch forming portion to give the requisite material to form the bottom or rear portion 22 with the relatively flat front portion 21 and at the same time to locate the juncture point 41 in a relatively lowered position compared with the confirmation at this point of garments now known. By the proper locating of the point 41, that is by the proper forming of the edge 29 and its associated notch 17, the necessary fullness can be given to the crotch and at the same time there is eliminated the usual tendency of such garments to rub or bind against the user at this point. It simply requires a judicious selection of length and form at the front edge 29 of the crotch section to raise or lower the point 41 as may be necessary to provide the desired smoothness of fit to the differently conformed body portion of the different purchasers.

The present disclosure has economic advantages when made as a factory production on large scale, in that the same size tubular member 10 such, for instance, as a 34 inch tube may be used to form different sized garments, the variation being made simply by varying the dimension of the relatively small crotch forming portions. The tubes when piled in flat condition can be readily cut to form the V-slits in front and rear and likewise the component crotch forming sections can be easily cut in bulk so that except for the gathering at the top, the complete garment can be fabricated simply by forming three seams 34, 37 and 38.

In use, articles of this character as heretofore constructed had a tendency to tear along the seam lines 37 and 38, but in this case these seams extend diagonally on the courses of the material, both in the body portion and in the crotch form portion and this disposition of the seams acts to resist such tearing possibilities.

I claim:

A bifurcated under-garment comprising a body portion forming the front, back, sides and the front, outer sides and rear of the legs of the garment, and a crotch portion completing the normally concealed inner sides of the two legs, the body portion consisting of a knitted tubular member initially having a straight lower edge and said lower edge slitted at its front and rear centers along bias lines and spread apart to form V-shaped front and rear notches at diametrically opposite points in the lower edge, said crotch forming portion comprising two similar sections, each of said sections being of quadrilateral form, having two opposing long and two relatively short edges, one of the long edges of each section forming the bottom edge of the inner side of the associated leg and the other three edges being each cut on the bias with the two short bias cut edges being curved and seamed to the body portion and the long bias cut edge being also curved and seamed to the companion section, the crotch forming portion having wide-spreading pointed ends, each forming an included angle materially greater than 90°, one of the pointed ends being wider than the other, fitting in and seamed to the bias cut lines forming one of the notches and the other pointed end similarly fitting in and seamed to the bias cut lines forming the other notch, whereby the crotch-forming portion is secured to the tubular member by seams all of which extend at angles to the texture of all of the fabric which forms the seams.

ISADORE LAWRENCE LESAVOY.
